CLAIM

The ornamental design for a toy figure, as shown and described.

DESCRIPTION

FIG. 1 is a perspective view of the toy figure of the invention;

FIG. 2 is a perspective view of the toy figure of FIG. 1 with legs in an alternative position;

FIG. 3 is a perspective view of the toy figure of FIG. 1 with a fireman helmet in phantom;

FIG. 4 is a front elevation view of the toy figure of FIG. 1;
FIG. 5 is a rear elevation view of the toy figure of FIG. 1;
FIG. 6 is a side view from the left of the toy figure of FIG. 1;

FIG. 7 is a side view from the right of the toy figure of FIG. 1;

FIG. 8 is a top view of the toy figure of FIG. 1; and,
FIG. 9 is a bottom view of the toy figure of FIG. 1.

The broken lines showing a helmet in FIG. 3 are for
illustrative purposes only and do not form part of the
claimed design.
